SAFETY JOINT FOR WELL SWABS

James E. Redpath, Oklahoma City, Okla.

Application January 13, 1949, Serial No. 70,668

6 Claims. (Cl. 103—202)

1

The present invention relates to well swabs, and more particularly to means for preventing fluid over-load.

Conventional well swabs usually consist of a tubate body having an exterior annular element of rubber which is adapted to contact and seal against the well casing. The body also includes a downwardly closing check valve which remains open when the swab is lowered into the casing through a column of well fluid, and which closes when the body is pulled upwardly.

In swabbing wells with such a swab, the swab is lowered into the casing on a wire line. Should the swab be lowered to an excessive depth below the top of the fluid column, the line often becomes overloaded to the extent that it is pulled in two when an attempt is made to raise the swab.

The prime object of the present invention is to provide a safety device which may be installed above a usual swab, and which when overloaded, releases fluid flow through the swab body.

Another object is to provide a safety device which contains its own check-valve, so that the check-valve in the swab may be eliminated.

A further object is to provide a device of this class in which the fluid pressure at which the passage is opened, may be positively and accurately controlled.

The device includes shear-pins for releasing the fluid load when an overload occurs.

Other objects will be apparent from the following description when taken in conjunction with the accompanying two sheets of drawings, wherein:

Figure 1 is an elevational sectional view taken along the longitudinal axis of the tool, the dotted lines illustrating a fragment of the upper end of a well swab, the tool parts being shown in their normal or flow preventing positions;

Figure 2 is a similar view showing the tool parts in open or flow permitting positions;

Figure 3 is a transverse sectional view taken substantially along the line 3—3 of Fig. 1;

Figure 4 is a similar view taken substantially along the line 4—4 of Fig. 1; and

Figure 5 is an enlarged fragmentary vertical sectional view detailing the check valve portion of the device.

Like characters of reference designate like parts in those figures of the drawings in which they occur.

In the drawings:

The reference numeral 1 indicates the upper end portion of a well swab having an axial bore 2 therethrough. The swab 1 is not a portion of

2

the device of the present invention, but is the device above which the tool of the present invention is adapted to function.

The device of the present invention, per se, includes a tubular body 10 having an axial bore which is separated into upper and lower compartments 11 and 12 by a set of radially spaced inwardly projecting vanes 13 having interstices or slots 14 therebetween.

10 Communicating with the upper chamber 11, is a plurality of lateral ports 15 which extend through the annular wall of the body 10.

The lower portion of the body 10 has a reduced bore 16 extending axially from the lower end 17 of the chamber 12 to the lower end of the body.

Exteriorly, the lowermost end portion of the body 10 is formed into an exteriorly threaded pin 18 by which the body may be rigidly yet removably attached to the upper end of the swab 1.

20 The device further includes an elongated valve member or shuttle which is indicated, as a whole, by the reference numeral 20. The member 20 consists substantially of an upper exteriorly threaded pin 21 formed above a cylindrical head 22 which has a reduced exteriorly cylindrical portion 23 therebelow. The upper portion of the pin portion 21 is solid, except for a transverse port 24 which extends through the pin adjacent its lower end. Below the port 24, the head 22 and the depending portion 23 are provided with an axial bore 25, the lower end of which is reduced in diameter and is formed to provide a seat 26 for a ball valve 27. A stop 40 is provided in said bore 25 above the seat 26.

25 The depending portion 23 of the member 20 has a groove surrounding its lower portion, and the groove is adapted to nest an annular packing member 28 which is made of some suitable resilient material such as rubber. The packing member 28 has a sealing fit with the wall of the chamber 11, and the portion 23 has a working fit with said wall.

30 Below and integral with the lower end of the depending portion 23, there is provided a tubular stem 29 which has a working fit with the inner edges of the vanes 13. The stem 29 has an axial bore 30 which extends from the seat 26 throughout the entire length of the stem. The lower portion of the stem 29 has a plurality of outwardly extending ribs 31 which are radially spaced to provide slots 32 therebetween. The ribs 31 reside within the lower chamber 12, and together act as a guide for the stem and portion 23.

35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

Although not so shown in the drawings, the stem 29 will be divided laterally through its

smooth portion, and the two sections thereof will be threadedly connected together. Such division of the smooth portion of the stem is necessary for assembly purposes.

The above described construction is such that the valve member is free to move longitudinally within the body 10, the portion 23 working in the upper chamber 11, the vanes 31 working in the lower chamber 12, and the smooth portion of the stem 29 working through the vanes 13 of the body 10.

When assembled for operative installation, the valve member 20 is moved to the lower end of its travel, and the wall of the body 10 and one of the vanes 31 are laterally bored to receive a shearpin 33. The pin is driven in place, and acts normally to hold the valve 20 against movement in the body 10.

When the valve member is thus held at the lower end of its stroke, the ports 15 are closed by the depending portion 23 thereof. The sealing element 28 then resides below the ports 15 (Fig. 1). During the bailing operation, the ball valve 21 seats upon the seat 26 when the device and the swab are being raised in the well casing, and when they are lowered through the fluid column in the well casing, the ball is raised off its seat by the fluid passing upwardly through the bore 2 of the swab, the bore 16 of the pin 18, the chamber 12, the bore 30 of the stem 29, the seat 26, the bore 25 of the depending portion 23, and outwardly through the lateral ports 24.

Should a fluid load in excess of the shear resistance of the pin 33 be placed upon the device, upward pull on the valve member will cause the pin to be sheared.

When this occurs, the valve member will be lifted to the upper end of its travel, or to the position illustrated in Fig. 2.

When the valve member 20 reaches the upper end of its permitted travel, the lower end of the depending portion 23 resides in the chamber 11 above the lateral ports 15. Well fluid is then free to enter the ports 15 and to flow downwardly in the body 10 by passing through the upper chamber 11, the slots 14, the slots 32 in the lower end of the stem 29, the lower chamber 12, and the bore 16 therebelow. The fluid may thereafter enter the bore 2 of the swab and flow therethrough back to the well casing.

After the pin 33 is once stripped, it may be drilled out and replaced so as to again put the device into condition for operation.

The pin 21 at the upper end of the body 10 is provided for the purpose of connecting the device to a conventional rope socket 35 on the lower end of a wire line 36 whereby the tool and swab may be operated.

It is pointed out that any desired plurality of the pins 33 may well be provided so as to properly regulate the shear resistance, or in other words, so as to properly regulate the load lifting capacity of the device. All lifting load which may be borne by the swab, is carried by the shear pin or pins.

Obviously the invention is susceptible to some change or alteration without defeating its practicability, and I therefore do not wish to be confined to the preferred embodiment shown in the drawings and described therein, further than I am limited by the scope of the appended claims.

I claim:

1. An overload safety device for well tools,

including: a body which is tubular throughout its length, said body having lateral ports extending outwardly from its bore, and the lower end of said body adapted to be attached to the upper end of a tubular well tool to form a continuation thereof; a tubular plunger-type valve member slidable in said bore to open and close said ports; a valve seat in the bore of said member; a downwardly closing valve for seating upon said seat; shear pin means for holding said member in position to close said ports; and means for attaching the upper end of said member to a lifting line.

2. Structure as specified in claim 1, in which the valve member has a lower guide portion which is longitudinally fluted to permit downward flow of fluid through the body when the member is raised above the ports.

3. Structure as specified in claim 1, in which a portion of the body wall is longitudinally fluted below said ports, to permit downward flow of fluid through the body when the member is raised above the ports.

4. Structure as specified in claim 1, in which the upper portion of the valve member has lateral passages extending from its periphery to its bore for admitting well fluid to said bore.

5. Structure as specified in claim 1, and an annular sealing element of resilient material surrounding the valve member for sealing with the wall of said body.

6. An overload safety device for well tools including: a tubular body having a longitudinally fluted annular restriction in its bore for dividing the same into an upper and a lower compartment; lateral ports through the wall of said body adjacent its upper end; means carried by the lower end of said body for coupling it to the upper end of a tubular well tool; a tubular plunger-type valve member having an exteriorly smooth cylindrical portion slidably disposed in the upper chamber of said body for closing and opening said ports; an exteriorly smooth stem portion depending from said cylindrical portion and passing downwardly through said fluted restriction into the lower chamber; radially spaced longitudinally extending guide vanes surrounding and integral with the portion of the stem which resides in the lower body chamber; lateral passages through the wall of said valve member adjacent the upper end thereof for admitting well fluid to the bore of said member; a valve seat formed in the bore of the cylindrical portion of said valve member to admit well fluid to said bore; a valve seat in the bore of said cylindrical portion of the valve member; a downwardly closing valve in said bore for seating upon said seat; means for attaching the upper end of said valve member to a swab line; and

7. A valve member for use in a well tool, having an exteriorly smooth cylindrical portion slidably disposed in the upper chamber of a tubular body for closing and opening lateral ports; an exteriorly smooth stem portion depending from said cylindrical portion and passing downwardly through said fluted restriction into the lower chamber; radially spaced longitudinally extending guide vanes surrounding and integral with the portion of the stem which resides in the lower body chamber; lateral passages through the wall of said valve member adjacent the upper end thereof for admitting well fluid to the bore of said member; a valve seat formed in the bore of the cylindrical portion of said valve member to admit well fluid to said bore; a valve seat in the bore of said cylindrical portion of the valve member; a downwardly closing valve in said bore for seating upon said seat; means for attaching the upper end of said valve member to a swab line; and a frangible pin means attaching said valve member to said body in position to close said lateral parts.
